UNITED STATES PATENT OFFICE.

MAURITS J. SANDIN, OF WILKINSBURG, PENNSYLVANIA, ASSIGNOR TO WESTINGHOUSE ELECTRIC & MANUFACTURING COMPANY, A CORPORATION OF PENNSYLVANIA.

REFILLABLE FUSE.

1,425,699.

Specification of Letters Patent. Patented Aug. 15, 1922.

Continuation of application Serial No. 273,024, filed January 25, 1919. This application filed June 4, 1921. Serial No. 475,043.

To all whom it may concern:

Be it known that I, MAURITS J. SANDIN, a citizen of the United States, and a resident of Wilkinsburg, in the county of Allegheny and State of Pennsylvania, have invented 5 a new and useful Improvement in Refillable Fuses, of which the following is a specification, this application being a continuation of co-pending application Serial No. 273,024, 10 filed January 25, 1919, by Joseph H. Procter and Maurits J. Sandin.

My invention relates to fuses and particularly to refillable-cartridge-fuse terminals.

One object of my invention is to provide 15 end-walls for a refillable-cartridge fuse that shall assist in alining knife-blade terminal members, provide packing for sealing the cartridge and, by being removable as units, transversely and from one side only of the 20 blade members, shall facilitate the operation of refilling the cartridge.

Another object of my invention is to provide a cartridge-fuse terminal that, for compactness, shall comprise a transverse web 25 of such dimensions as to permit of its passage through the tube and of a form that, when it is disposed in co-operative relation with a complementary removable plate therefor, constitutes a single composite disk of 30 uniform thickness and greater diameter than the bore of the tube.

In practicing my invention, I provide a fuse cartridge having blade-contact-terminal members at the ends thereof and transversely-disposed closure, alining and packing members embracing the blades and of such relation to one another as to minimize the total thickness of the end walls of the cartridge.

40 Further, these members are connected to permit the removal thereof as a single unit and formed to permit the removal, transversely and from one side only, of the blade members.

45 Figure 1 of the accompanying drawings is a longitudinal view, partially in elevation and partially in section, of a cartridge fuse embodying my invention;

50 Fig. 2 is an interior end view of the same, taken along the line II-II of Fig. 1;

Fig. 3 is an exterior end view of the device as illustrated in Fig. 1;

Figs. 4, 5, 6, 7 and 8 are detail views of the component members of an end wall embodied in my invention; and

55 Figs. 9 and 10 are detail views of modifications of a terminal member embodied in my invention.

A tubular body member 1, of fiber or other suitable insulating material, is threaded, at its ends, to receive ferrules 2 having inwardly projecting flanges 3.

60 Terminal blade members 4, preferably of copper, are disposed partially inside and partially outside the ends of the member 1. 65 Bolts 5, or other suitable means, secure a fusible element 6 between apertured inner end portions 7 of the members 4 and the latter may be attached, by the outer end portions 8 thereof, to terminal jaws or clips 70 (not shown) of an electric circuit. The portions 8, being of greater width than the portions 7, provide shoulders 9 against which rest transversely-extending webs 10 of substantially fan shape and having central openings 11 therein conforming to the 75 portions 7. The webs 10 rigidly embrace the portions 7 to form a gas-tight joinder therewith as, by being soldered, wedged or otherwise suitably secured thereto.

70 As illustrated in Fig. 4, each web 10 comprises a flat piece of copper or other suitable material of substantially fan shape. An initially centrally-disposed three-sided rectangular tongue portion 12 is pressed out of 80 the plane of the web 10 and bent into and around a notch 13 in one edge of the same to constitute a positioning lug, Figs. 1, 2 and 3, that engages a notch 14 at the end of the member 1, and prevents turning of the 90 terminal member 4 with respect to the member 1.

85 The tongue portion 12 may be formed with a relatively wide curve 15, Fig. 9, as a precaution against fracture at the bend 95 and extend only to the edge of the web 10, in which form the notch 13 is omitted.

A discoidal plate member 16, preferably of the same material and thickness as the web 10, is centrally recessed and formed to closely embrace the web 10 in edge-to-edge relation therewith, whereby the member 16 and the web 10 constitute substantially a single 100 disk of uniform thickness and greater di-

ameter than the bore of the tubular member 1.

A packing washer 17, of leather or other suitable material, having a centrally disposed slot 18 adapting it to be slipped transversely over the portion 8 of the member 4, may be removably positioned between a metal washer 19, having a centrally disposed slot 20, and the member 16 by screws 21 10 or other securing members that extend through holes 22 in the members 16, 17 and 19 to form a removable compound washer or unitary-wall structure 23 for mounting on the portion 8 adjacent the web 10 to permit the latter and the member 16 to assume the above-described single-disk relation.

In order to prevent longitudinal displacement of the member 16 with respect to the web 10 and the terminal member 4, the portion 8 is provided with an edge notch 24 in which portions of the washers 16 and 19 are disposed adjacent the plate 10.

In Fig. 9, projections 25, suitably formed, as by knocking up the surface of the member 4, serve as means for preventing the longitudinal displacement of the member 23.

In Fig. 10, a transverse groove 26, in one or both sides of the member 4, serves to prevent the displacement of the member 23.

When the wall structure 23 is placed in operative relation to the member 4 and the web 10, it is maintained in position against the end of the member 1 by the flange 3 of the ferrule 2. The packing washer 17 covers the engaging edges of the web 10 and the member 16 to retard the escape of gas therebetween and may be of slightly greater diameter than the washer 19 to retard the escape of gas between the latter and the flange 3.

When the element 6 is volatilized, removal of the ferrules 2 from the member 1 permits the withdrawal of the terminal members 4. One or both of the wall structures 23 at the ends of the member 1 may be removed from the members 4 before or after replacing the volatilized element in position between the portions 7. Thus, the members 4, connected by a new element 6, may be placed in the member 1 from either end thereof and the wall structures 23 replaced, after which the ferrules 2 may be screwed into position on the member 1.

The unitary-wall structure or compound washer 23 is adapted to be attached to, and detached from, the member 4 by a single transverse sliding movement towards or from one edge only of the latter, thereby greatly facilitating the manipulation of the device.

The arrangement further serves as an efficient gas and flame check to minimize the danger to surrounding objects, forms a neat and compact device, and by reason of the

relation existing between the web 10 and the member 16, reduces the end wall to substantially a minimum of thickness and material.

While I have shown and described particular forms of my invention, many changes 70 may be effected therein, without departing from the spirit and scope thereof, as set forth in the appended claims.

I claim as my invention:—

1. A refillable cartridge fuse comprising 75 a tubular body member, a terminal member disposed at the end thereof and having a transverse web portion permitting the passing of the terminal member through the bore of the tubular member, a member co-operating with said web portion to constitute a closure wall of single thickness across the end and of greater diameter than the bore of the tubular member, removable means for maintaining the members constituting said closure wall in operative relation on said terminal member when the latter is separated from said tubular member, a removable ferrule for maintaining said closure wall in operative position, and packing 85 means overlying the joints between the component members of said closure wall and between said closure member and said ferrule.

2. A refillable cartridge fuse comprising 95 a tubular body member, a terminal member disposed at the end thereof and having a fixed transverse web portion, the greatest dimension of which is less than the diameter of the bore of the tubular member, and a member disposed in the plane of, and co-operating with, said web portion to constitute 100 a plate of single thickness across the end of the tubular member and greater in diameter than the bore thereof.

3. In a refillable cartridge fuse, the combination with a tubular body member, of a closure and terminal device therefor comprising a plate member, the greatest dimension of which is less than the diameter of the bore of the tubular member, and second plate 110 member co-operating with, and disposed in the plane of, said plate member to constitute a single composite plate of uniform thickness across the bore of said tubular member.

4. In a refillable cartridge fuse, the combination with a tubular body member having a notched end, of a closure and terminal member therefor comprising a blade member having a transversely projecting web portion, said web portion constituting a substantially flat plate having a central portion pressed outwardly to create an opening for the reception of the blade member, and the material previously occupying the space of said opening being bent around to the outer 125 edge of said plate to constitute a positioning lug for co-operation with said notch.

5. In a refillable cartridge fuse, the combination with a tubular receptacle, a terminal member having a laterally disposed web 130

- portion at the end of said receptacle and a removable ferrule, of a unitary removable means for closing the end of said receptacle and positioning said terminal member comprising a plate for co-operating with, and disposed in the plane of, said web to constitute a composite transverse closing plate for said tubular member, a slotted packing washer for abutment against said composite plate and a slotted metal washer to be slipped over said blade member.
6. A refillable cartridge fuse comprising a tubular body member, a terminal member disposed at one end thereof and having a transverse web portion permitting the passing of the terminal member through the bore of the tubular member and a plate
- 5
- 10
- 15
- 20
- 25
- 30
- member co-operating with, and disposed in the plane of, said web portion to constitute a composite transverse wall plate of single thickness.
7. In a refillable cartridge fuse, the combination with a tubular receptacle, of a terminal member therefor and a closure comprising relatively movable complementary discoidal members of unequal thickness and forming, when operatively associated, a closure of uniform thickness for the tubular receptacle, the thickness being substantially equal to that of one of the said members.
- In testimony whereof, I have hereunto subscribed my name this 2nd day of June, 1921.

MAURITS J. SANDIN.
